(57) **CLAIM**

The ornamental design of a smoking apparatus substantially, as shown and described.

DESCRIPTION

FIG. 1 is a perspective view of a smoking apparatus showing my new design.

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The features shown in broken lines in the various Figures form no part of the claimed design.

The invention pertains to an ornamental design for an article of manufacture. The article of manufacture can vary widely and is not limited to the scale shown herein. The article may be scaled to different sizes.
